VACUUM VAPORIZATION-CONDENSATION
COOLING SYSTEM

Melville W. Beardsley, Venice, Calif.

Application October 10, 1950, Serial No. 189,466

15 Claims. (Cl. 62—169)

1

My invention relates generally to the cooling and refrigeration of comestibles, and more particularly, to the pre-cooling of such produce as lettuce, sweet corn, prior to its shipment. A method and apparatus for this general purpose are disclosed in my co-pending application, Serial No. 146,784, filed February 28, 1950, and entitled Method and Means for Cooling Produce by Use of Reduced Pressures, of which the present application is a continuation-in-part.

One customary practice in cooling produce such as lettuce prior to and during shipment thereof is to interlayer the produce with crushed ice while it is being packed into the shipping crates, and also to cover the closed crates with ice in the refrigeration cars in which they are shipped. As stated in the above-identified co-pending application, the disadvantages of the conventional procedure just described are that the crushed ice tends to bruise tender vegetables such as lettuce; the water from the melting crushed ice causes considerable deterioration and discoloration of the produce during shipment thereof, and is generally a nuisance; and the crushed ice, in spite of great care in distribution, does not maintain as uniform a temperature throughout the body of the packed shipment as is desired. Still further, the operation of packing the crushed ice into crates or other containers with the produce is a costly and time-consuming phase of the packing and shipping operation.

The above-identified co-pending application discloses a method and means for precooling produce by means of a vacuum causing evaporation of the surface moisture therefrom, a process described generally as "vacuum cooling." The present invention concerns further improvements in the method and apparatus for vacuum cooling. In current practice, the vacuum cooling process employs steam jet pumps to evacuate the air and water vapor from a closed chamber containing the produce in process. Steam jet pumps have proven more satisfactory for this purpose than mechanical pumps because they are better adapted to pump relatively large volumes of vapor generated by the evaporation of moisture from the produce. A disadvantage of steam jet pumps is, however, that they consume large quantities of steam and thus require a large boiler and steam condensation system. For this reason, vacuum cooling plants of the steam jet pump type are comparatively large, heavy and expensive, and must necessarily be of a permanent installation type.

Bearing in mind the general purposes of vac-

2

uum pre-cooling and also the fact that steam-operated plants currently in use are of a permanent type, it is a major object of the present invention to provide a light-weight, portable, vacuum pre-cooling plant adapted especially for use with seasonal produce such as lettuce.

Another object of the invention is to reduce the size and expense of vacuum pre-cooling plants even of the permanent installation type.

10 A further object of the invention is to provide for the use of ice in connection with the process of vacuum cooling, and also for a minimum of handling of such ice without the necessity of placing the same in direct contact with the produce being cooled.

Yet another object of the invention is to provide a system adapted for the use of mechanical refrigeration in connection with the vacuum cooling process.

20 A still further object is to reduce the power requirement of a vacuum cooling plant.

An additional object is to increase the speed and facility with which produce may be pre-cooled by the vacuum cooling method.

25 Yet another object is to provide a vacuum cooling plant in which the refrigeration and vapor condensing unit is separate from and readily detachable from the main produce-containing chamber, whereby the condensation unit may be used successively with a number of different produce-containing chambers.

30 A still further and general object is to provide apparatus for materially increasing the speed and efficiency of ice refrigeration from the standpoint of the theoretical absorption capacity of the ice.

35 Yet another object is to provide in a vacuum cooling system, efficient means for removing water in an ice-vacuum cooling refrigeration system, efficient means for removing water from the refrigerating chamber without wetting the produce.

The foregoing and additional objects and advantages of the invention will be apparent from 40 a consideration of the following detailed description of several forms thereof, such consideration being given likewise to the attached drawings, in which:

45 Figure 1 is a side elevational view of a presently preferred form of the invention using ice, and in which a pump and refrigerated condensation unit is mounted on the tractor portion of a truck-trailer combination, and in which a produce-containing, cooling chamber is mounted on the trailer portion;

55

Figure 2 is an enlarged elevational longitudinal section taken through the condensation and treatment chambers of the apparatus shown in Figure 1;

Figure 3 is an enlarged elevational section taken through a modified form of condensation chamber in which refrigerating coils are employed in place of the ice shown in Figure 2; and

Figure 4 is a further modified form of the invention employing an external ice bunker in place of the internal ice bunker of the apparatus shown in Figure 2.

Briefly, the apparatus employing my invention comprises a main produce-containing chamber 11 and a vapor-condensing chamber 15, the two chambers being interconnected by means of a flexible conduit having a quick-disconnect joint or fitting 27 therein. Incorporated in the condensing chamber unit is a vacuum pump 29 and a cold body to effect condensation of moisture, such body being, for example, the ice 17 shown in Figure 2, or mechanical refrigeration cold coils 39 in the form shown in Figure 3.

The quick-operating connection joint 27 provided in the interconnecting conduit 16 provides for the successive connection of the condensation chamber 15 with a number of different main chambers 11.

Before proceeding with a detailed description of the apparatus embodying the present invention, the principles of operation will be described briefly as follows. The first principle made use of is that evaporating moisture absorbs heat of evaporation from surrounding media. Thus, if the surface moisture on, let us say, a head of lettuce is caused to evaporate by reducing the surrounding vapor pressure, the heat of evaporation necessary to cause the same will be absorbed from the head of lettuce, thus cooling the same. This principle is also employed in the apparatus described in the above-identified co-pending application.

The second principle employed in the present invention is that vapor brought into contact with a surface colder than the dew point of such vapor at its then pressure will cause the vapor to condense with the result that a corresponding amount of heat is released by the vapor and absorbed by the cold surface. Such condensation also, of course, results in a reduction of pressure if it is accomplished in a closed chamber.

The third principle employed herein is that the vapor pressure of a given liquid depends on the temperature thereof; thus, if two vessels containing separate bodies of the same liquid at different temperatures are interconnected and all air and other non-condensable gases are removed, vapor of the liquid will flow from the vessel of higher temperature to the vessel of lower temperature because of the higher vapor pressure of the higher temperature liquid.

These three general principles are employed in the present apparatus by placing in one chamber the material to be cooled and in the connected chamber, means for maintaining a low temperature; and then removing the air and non-condensable gases from the two interconnected chambers. It will be apparent that, as the air and non-condensable gases are removed, the pressure in the two chambers will ultimately be reduced to a value equal to the vapor pressure of the surface moisture present on the produce. At this point, the absolute pressure in the condensing chamber is approximately equal to the vapor pressure of the surface moisture, but according

to Avogadro's law, it is comprised of the lower vapor pressure of the colder moisture (or ice) plus the partial vapor pressure of the air and non-condensable gases which are also present.

5 As air is continuously removed from the condensing chamber, the total pressure therein will be reduced until, when all air and other non-condensable gases are removed, the total condensing chamber pressure will become equal to the vapor pressure of the colder condensate or ice.

Under the conditions last above described, vapor will flow at high velocity from the main chamber to the condensing chamber. The vapor continues to be boiled off the produce and to flow 15 into the condensing chamber until the vapor pressure in both chambers is substantially equal. This condition of equality, of physical necessity, means that the surface moisture on the produce has been reduced to the same temperature as 20 the moisture or ice in the condensing chamber. For leafy produce such as lettuce, this is tantamount to a reduction to this temperature of the entire mass of the produce. Thus, in summation, it is seen that the vacuum cooling process 25 consists in removing heat from the produce and transmitting the same to ice or other refrigerant through the medium of evaporated and recon-densed vapor.

From the preceding discussion, it will be seen 30 that when the air has been substantially removed from the two chambers, there is theoretically no need for further evacuation. I have found by experience, however, that there is still a substantial amount of air present in the chambers by the time the point of rapid evaporation 35 and flow of water vapor commences therein. In addition to the condition just stated, there may be a slight amount of air leakage in the chambers, and furthermore, non-condensable gases, such as carbon dioxide, are given off by the produce being treated. Thus, I have found it necessary and desirable to continue the evacuation, though at a reduced rate, throughout the process in order that the cooling will continue at a maximum rate.

45 Whenever any small amount of air or other non-condensable gas is present in the condensing chamber, it will, according to Avogadro's law above-mentioned, add its partial pressure to that of the vapor pressure of the condensate, so that 50 the total may be great enough to equal the vapor pressure of the surface moisture on the produce, and thus stop the entire process. Furthermore, if any air is allowed to remain in the condensing chamber, even though the partial pressure thereof 55 may not be sufficient, theoretically, to halt operations, it soon collects in an insulating blanket on the ice or other condensing surface and prevents or greatly inhibits further condensation. The formation of such a blanket is due to the 60 fact that the condensation at the cold surface removes the water from the air-water-vapor mixture thereat, leaving relatively pure air. Thus, it is of further advantage to continue the pumping 65 during the entire cooling cycle in order to keep the aforesaid blanket of air from forming and to continuously draw water vapor into contact with the condensation surface.

In the preferred form of the apparatus illustrated in Figure 1, the main chamber 11 is charged with produce while the connected condensation chamber 15 is charged with ice. The chambers are thereafter substantially evacuated of air, the heat transfer starts automatically and 70 is allowed to continue until the desired pre-

cooling temperature of the produce has been reached.

An important feature of the present process is that substantially no work or energy is expended in pumping vapor out of the main chamber containing the material being processed, substantially the only material removed therefrom being air.

It will be realized that this is a major advantage of the present equipment over apparatus employing steam jet pumps and continuing the pumping operation to reduce the vapor pressure in the treatment chamber. In the latter type of apparatus, the major portion of all the energy required is used in pumping water vapor out of the treatment chamber.

As described in my above-mentioned co-pending application, I have found it possible to closely calculate the amount of ice required to produce a given reduction in temperature in a given weight of produce. Experience has shown, however, that often an undesirable amount of time and labor is required to load the chamber with a calculated amount of ice. Furthermore, it is usual practice to provide a safety factor by placing in the condensing chamber slightly more ice than the theoretical amount necessary to produce the desired cooling effect. Thus, there is a residuum of ice after the process has been completed which must usually be disposed of because it is of odd and undesirable shape for optimum operation.

As a means of reducing this labor and undesirable ice residuum, I have found is desirable to make the condensing chamber sufficiently large to contain enough ice for cooling several loads of produce; thus, the ice can be loaded relatively infrequently and without regard to the exact amount needed to pre-cool any particular load of produce.

As a means of accelerating the cooling process, particularly toward the end of a cycle, I have found it expedient to spray on the cold surface in the condensing chamber a chemical solution which lowers the melting temperature of ice and also reduces the vapor pressure of condensate formed therein.

Referring now to Figure 1 for a more detailed description of the preferred form of apparatus embodying the present invention, it will be seen that the treatment chamber 11 is of cylindrical configuration, having a hinged access door 13 formed in one end thereof, and a simple circular bulkhead closing the other end. The chamber 11 is mounted on a trailer 51 which is adapted to be towed by a truck 50 carrying the condensation chamber 15 and the vacuum pump 20, together with other refrigeration equipment. During the time that the cooling process is in operation, the main chamber 11 is connected to the condensation chamber 15 through the interconnecting conduit 16 having the quick-disconnect joint 27 therein. The interconnecting conduit 16, while adapted to withstand external atmospheric pressure when the interior thereof is substantially evacuated, is made flexible in order to facilitate operation of the joint 27 and also to permit operation of the truck-trailer 50-51 while the cooling process is continuing.

A valve 16a is incorporated in the interconnecting line 16 and manually operable to close the chamber 11 so that the vacuum therein may be maintained even though the chamber 11 is disconnected from the condensing chamber 15.

As seen best in Figure 2, a series of conveyor

rollers 14 is mounted in the chamber 11 to receive crated produce for movement into the chamber in conventional roller conveyor manner. A flow-directing baffle 38 is installed under the conveyor rollers 14, extends completely across and throughout the length of the chamber 11, except for a small gap adjacent the access door 13, and serves to establish a uniform vapor flow path out of the chamber 11, as indicated by the flow arrows in Figure 2.

At the top of the condensing chamber 15 is a hinged and sealed bulkhead type door 19 through which ice 17 may be loaded into an internal ice compartment 30 within the chamber 15. The ice compartment 30 is formed with a heat-conducting inner wall 18, having a sloping bottom so as to slide the ice forwardly against the forward wall of the chamber 15.

A vacuum pump 20 is connected by a suction line 21 to the interior of the chamber 15 adjacent the lowest point in the ice compartment 30. At the lowermost point in the compartment 30, a condensate drain pipe 24 serves to drain away condensate and melted ice to a condensate tank 23 which may be conveniently mounted at any point substantially below the lowermost point in the chamber 15. An air inlet valve 45 is connected in the suction line 21, and is selectively operable to admit air to the system after completion of the cooling cycle.

The system illustrated in Figure 2 operates as follows. After the ice 17 and the produce in crates 12 have been loaded into the respective chambers 15 and 11, and the doors 13 and 19 have been closed, an air-tight system containing the ice 17 and produce crates 12 at ambient temperature is established. Air is then pumped out of the system by means of the pump 20 through the conduit 21, the inner end of which is connected to a series of laterally disposed exit ports 28 in the inner wall of the ice compartment 30 adjacent the bottom thereof. By this arrangement all gas, whether air or water vapor, which is removed from the interior of the cooling chamber 11, must pass through the condensing chamber 15 and the inner ice compartment 30 in close proximity to the surface of the blocks of ice 17 therein. The water vapor constituent of the moving gas mixture is largely removed by condensation of the ice 17, thus making it necessary for the pump to move only substantially pure air. This, in turn, makes possible the use of a pump of relatively small volumetric capacity, as compared with vacuum cooling systems which operate by pumping out all gases including evaporated water vapor.

When the total pressure in the cooling chamber 11 and in the condensing chamber 15 is equal to or slightly greater than the vapor pressure of the moisture on the produce, then the system is in equilibrium and will remain so if the pumping is discontinued. However, if the pumping is continued past the point where the system total pressure is equal to the vapor pressure of the produce moisture, then boiling of the produce surface moisture occurs. This boiling will continue until the vapor pressure of the moisture in the cooling chamber 11 is equal to the total pressure in the condensing chamber 15. Thus, if all air and non-condensable vapors are removed from the condensing chamber 15, the total pressure therein will be that corresponding to the moisture on the surface of the ice. Therefore, moisture in the cooling chamber 11 will continue to evaporate until the moisture tem-

perature in the same is the same as the moisture on the surface of the ice 17, and the condensing chamber 15.

During the cooling process, the vapor formed by the evaporation of the produce surface moisture flows into the condensing chamber 15 through the interconnecting conduit 16, and is caused by a deflecting baffle 29 to impinge on a sloping heat transfer surface 26 down which is flowing water consisting of melted ice and condensate.

Since this water flowing down the surface of the sloping wall 26 has a temperature of approximately 32 degrees, it causes condensation of a substantial proportion of the water vapor impinging against the undersurface and absorbs heat therefrom. Thus, the mixture of condensate and melting ice approaches the temperature of the vapor impinging upon the wall 26 as such liquid mixture leaves the compartment 15 through the drain pipe 24.

That portion of the vapor which is not condensed by impingement against the heat exchange surface 26 passes, as indicated by flow arrows, around the substantially horizontal baffle 29 and along the outer surface of the ice compartment wall 18, up to the top of the ice compartment 30 where it comes in direct contact with the ice 17. Since the vacuum pump 20 is continuously operating, any air or non-condensable gas that is mixed with the vapor will be drawn through the ice-containing chamber 30, and out through the exit ports 23 after passing in intimate heat transfer contact with the ice 17 so that substantially all vapor is condensed.

As the ice 17 is melted by the released latent heat of evaporation, the melted ice and condensate drains, as aforesaid, to the bottom of the ice compartment 30 and out through a series of laterally disposed drain tubes 31 into an inner drain reservoir 33. When this small reservoir 33 is full, the liquid therein overflows and down the sloping bottom surface 26, as described. This system of drain tubes 31 and the reservoir 33 serves as a trap at the bottom of the ice compartment 30 so that the vapor must follow the flow path previously described and therefore enter the ice compartment 30 at the top and pass downwardly therethrough. In this way, maximum condensation effect is achieved.

In this connection, I have found that, as compared to other flow directions, a generally downward flow path over the ice, or other cold condensing surface, is of considerable advantage and effects a considerable improvement in efficiency since air, being more dense than water vapor, will tend to flow naturally to the bottom of the chamber containing the condensation surface, into the discharge ports 28, and thence to the vacuum pump. If, on the contrary, the flow of vapor-air mixture were to be upward past the condensing surface, the air would tend to form an insulating blanket against the surfaces, since the light water vapor constituent tends to rise and the heavier air constituent tends to slide down along the cold surface counter to the flow direction, thus preventing efficient vapor condensation instead of passing on for removal by the vacuum pump.

In order to increase the rate of cooling as the produce temperature approaches 32 degrees, it has been found desirable to lower the surface temperature of the ice 17 and also to lower the vapor pressure of the condensate and melted ice in the condensing chamber 15. This reduction

of ice surface temperature and vapor pressure is accomplished in the present instance by injecting a solution containing a chemical such as common salt or calcium chloride against the ice surface. For this purpose, in the present embodiment a solution tank 34 is provided and connected by a suitably valved conduit 36 to the interior of the ice compartment 30 so that by operation of the valve 36a in the conduit 36, solution is sprayed through a set of interior nozzles 35 onto the ice 17.

Efficiency of the system is also greatly improved by covering the condensing chamber 15 with a layer of insulating material 37 in order that heat will not be absorbed from atmosphere. Such insulation is particularly necessary on the sloping heat transfer surface 26 to prevent the melted ice and condensate mixture from absorbing heat and increasing its vapor pressure, thus reducing overall efficiency. Unless the vapor pressure of all liquids in the chamber 15 is maintained as low as possible, the final desired temperature may not be reached, even though pumping is continued and all of the ice consumed.

An alternate form of the invention is illustrated in Figure 3 wherein cold coils 39 of a mechanical refrigeration system of known design are employed instead of ice in the condensing chamber 15. In this modified form, refrigerating coils 39 of a conventional mechanical refrigerator are mounted in heat transfer contact with the bottom surfaces of a number of horizontally disposed condensate trays 40.

A compartment 30a, analogous to the ice compartment 30, of the previous embodiment, is provided in the form shown in Figure 3, and the trays 40 are staggered and spaced vertically in the compartment 30a so as to act as baffles and provide a tortuous downward path for vapors passing through the compartment. This arrangement causes the air and water vapor mixture moving through the condensing chamber 15 to sweep in close contact with both the upper and lower surfaces of the trays 40, and the coils 39 secured to the undersurfaces thereof. The refrigeration equipment necessary to supply cold refrigerant to the coils 39 is of conventional design and need not be described in detail herein. Such a mechanical refrigeration plant can be mounted on the tractor 50 and powered either by the prime mover of the tractor itself, or by a suitable auxiliary power plant.

The operation of the modified form shown in Figure 3 is similar to that of the previously described embodiments. Vapor flows from the main chamber 11 through the interconnecting conduit 16 into the condensing chamber 15 and is deflected by a baffle 29 to impinge on the sloping liquid-heat transfer surface 26. Uncondensed vapor and any entrained air leaving the surface 26 flows upwardly, as indicated by the flow arrows in Figure 3, to the top of the compartment 15 and thence downwardly over the coils 39 and their adjacent trays 40 to discharge ports 42, thence into the suction line 21 leading to the vacuum pump 20. Condensate from the vapor condensing on the coils 39 drips downwardly into the trays 40 until these are filled to the level of an overflow tube in each, identified by the reference character 41. After reaching this level, additional condensate runs out of the overflow tubes 41 into small sealing reservoirs or traps 70 located at the ends of each of the tubes 41 and mounted to the wall 18a of the inner chamber 30a. When the reservoirs 70 are filled with condensate, the

same overflows and drops downwardly to the sloping heat exchange surface 26 and out the condensate drain pipe 24.

The purpose of the condensate trays 40 is to retain a substantial mass of liquid condensate so that it may be frozen into ice by the refrigerating coils 39 during the period in which the main chamber 11 is being unloaded and reloaded with additional produce for the next cycle. By this means, the refrigerating plant supplying the coils 39 can be operated continuously, the trays 40 and the frozen condensate therein serving as a heat absorbing ballast and thus building up the heat absorbing capacity of the system. This arrangement makes possible the use of a comparatively smaller refrigerating plant (for a given rate of cooling) than would be required if all the heat of vapor condensation were absorbed directly by the refrigerating coils during the initial part of the cooling cycle. The same general result can be accomplished by spraying water over the refrigerating coils during the loading period. This water, if sprayed at the proper rate, will form ice on the refrigerating coils and thus build up heat absorbing capacity as set forth above.

When refrigeration coils are employed, as shown in Figure 3, the flow path of air and vapor might become blocked because of the accumulation of ice on the coils, particularly on the coils adjacent the discharge ports 42. This is particularly true when a counterflow system is employed in which the refrigerant enters the coils at the end adjacent the ports 42.

As a means of preventing the aforesaid blocking of flow due to the formation of ice, I have found it expedient to provide a flexible flap or membrane 43 mounted so that its free edge rests on a transverse length 39a of the refrigerating coils 39 immediately adjacent the discharge ports 42. With this arrangement, when the ice formation blocks the normal flow path, the suction created in the vacuum line 21 lifts this membrane 43 sufficiently to permit the continued flow of air and vapor out of the discharge ports 42, such continuous flow passing in intimate contact with the aforesaid coil length 39a.

Additional, or in some cases alternative means are provided for preventing the blocking of flow by the formation of ice, such additional means being a nozzle 44 mounted adjacent the port 42 and adapted to spray a chemical solution of freezing point lowering material such as calcium chloride whereby to melt the accumulated ice and unblock the flow. The addition of such a chemical solution also has the favorable effect of reducing the vapor pressure of the condensate contained in the condensate pan 49 immediately below the exit port 42.

In the embodiment illustrated in Figure 4, the released latent heat of evaporation is removed from the condensation chamber by conduction through the walls themselves. To produce this effect, the condensation chamber 15a is cylindrical in form and a portion of the outer surface is cooled by the application of ice 17 thereagainst, the ice being supported in an external bunker 71. In the operation of this embodiment, vapor enters the condensation chamber 15a through the interconnecting conduit 16 and is deflected by the baffle 29 in the manner of the previous embodiments. Thus, the incoming air-vapor mixture is caused to follow the inner wall surface of the chamber 15, as indicated by the flow arrows. As the vapor flow follows the refrigerated surface, the vapor condenses and the condensate drains

to the bottom of the chamber 15a where it is removed through the drain pipe 24a, in the manner previously described. Any air or non-condensable gas mixed with the vapor is carried on around the wall surface to the laterally spaced exit ports 28a, and leaves the chamber in the manner previously described.

As the heat of vaporization from the condensing vapor is conducted through the wall of the chamber 15a, the ice 17 is melted and the resultant water drains down into a liquid flow space 52 between the bunker 71 and the chamber 15a. In the space 52, the melted ice-water is constrained to flow along the exterior surface of the condensing chamber walls so that an additional heat transfer is effected between the condensing vapor and the melted ice-water. By this means, maximum refrigerating efficiency is obtained since the melted ice-water is heated to nearly the same temperature as the entering vapor before it finally leaves the system through an overflow ice drain 53.

A nozzle 54 serves to introduce a melting point reducing solution into the contact surface between the exterior surface of the chamber 15a and the ice 17, thus reducing the temperature at this point.

In order to achieve a maximum possible rate of cooling, I have found it desirable and expedient to incorporate within the condensation chamber 15a (or in the chamber 15 of the previous forms), a blower 55 which increases the rate of condensation on the inner chamber wall surface. The blower 55 is arranged to discharge onto the inner wall surface, as indicated in Figure 4. The increased velocity of surface flow and the turbulence created by this blower increase the rate of condensation, both by removal of the aforementioned air blanket that tends to form on the condensing surface, and also by agitating and moving the condensed water so that the uncondensed vapor obtains more direct contact with the cold wall surface.

In all of the embodiments illustrated, air is admitted to the system after the desired pre-cooling temperature is reached by means of the air inlet valve 45 connected to the end of the pump suction line 21. All of the illustrated embodiments employ the same method and means for dumping the condensate drain tank 23 at the end of the pre-cooling cycle. Referring to Figure 2, it will be seen that a condensate tank discharge valve plug 25 is attached to one end of a pivoted lever 60 which is supported on a pin joint 61, and has a counterweight 63 thereon on the opposite side of the pin 61 from the valve plug 25. A metal actuating bellows 64 is connected at one end to the lever arm 60 and at the other end to a fixed portion of the structure. The interior of the actuating bellows 64 is communicated with the main suction line 21 by a tube 65 and a fitting 66.

Thus, when the vacuum pump 20 is started at the beginning of any particular cooling cycle, the pressure in the actuating bellows 64 is reduced, causing the same to contract under the influence of atmospheric pressure. Such contraction of the bellows 64 raises the valve plug 25 into the adjacent discharge valve seat. When seated, the valve is further held shut by the action of atmospheric pressure thereon, and no leakage occurs at this point. The position of the counterweight 63 is so adjusted that only a small force need be exerted by the bellows 64 to close the plug 25 as aforesaid. When air is readmitted to the system and thus also to the bellows 64, it and the

weight of the water above the plug 25 cause the valve to open, dumping the contents of the condensate tank 23.

It will be noted that in all of the forms illustrated the flow through the condensation chamber is so organized that air-vapor passing therethrough must pass in heat transfer relation with the cold condensation surface before reaching the exit ports. Also baffle means are provided in each case to prevent any substantial body of condensate water from being located immediately adjacent the exit ports. This creates a condition of optimum efficiency in that relatively great proportions of air are moved by the pump as compared to the vapor moved thereby.

While the forms shown and described herein are fully capable of achieving the objects and providing the advantages hereinbefore stated, they are capable of some modification without departing from the spirit of the invention. For this reason, I do not mean to be limited to the forms shown and described, but rather to the scope of the appended claims.

I claim:

1. In a vacuum cooling system of the class described: a hermetic enclosure having a sealable access door to receive material for treatment in said enclosure; evacuation and condensation means including a chamber having a cold surface therein, a vacuum pump connected to said chamber to evacuate the same, and conduit means connected to said enclosure to intercommunicate said chamber and enclosure; and means to direct liquid condensate forming on said cold surface to a point in said chamber adjacent the influx of vapor and air from said conduit means whereby the air-vapor mixture drawn from said enclosure through said chamber first passes in heat transfer relation past said condensate and then in contact with said cold surface.

2. In a vacuum cooling system of the class described: a hermetic enclosure having a sealable access door to receive material for treatment in said enclosure; evacuation and condensation means including a chamber having a cold surface therein, a vacuum pump connected to said chamber to evacuate the same, and conduit means connected to said enclosure to intercommunicate said chamber and enclosure; means to direct liquid condensate forming on said cold surface to a point in said chamber adjacent the influx of vapor and air from said conduit means; and baffle means positioned between said influx and the point of connection of said vacuum pump and said chamber whereby air-vapor mixture drawn from said enclosure through said chamber first passes in heat transfer relation with said condensate and then in contact with said cold surface.

3. In a vacuum cooling system of the class described: a hermetic enclosure having a sealable access door to receive material for treatment in said enclosure; a chamber communicated with said enclosure; a mechanical refrigerator having the cold coils thereof positioned in said chamber; a vacuum pump connected to said chamber to evacuate the same and said enclosure; and reservoir means in said chamber to retain a body of water in heat transfer contact with said coils whereby to provide a heat-absorbing ballast therein.

4. In a vacuum cooling system of the class described: a hermetic enclosure having a sealable access door to receive material for treatment in said enclosure; a chamber communicated with

said enclosure; a mechanical refrigerator having the cold coils thereof positioned in said chamber; a vacuum pump connected to an exit port in said chamber to evacuate the same and said enclosure; and yieldable flow constricting means positioned adjacent said exit port of said chamber and adapted to constrain exiting gases to flow past a coldest portion of said coils, said yieldable constricting means being adapted to move to prevent blocking of said exit port as ice builds up on said coldest coil portion.

5. The method of vacuum cooling comestibles having surface moisture thereon comprising the steps of: placing said material to be cooled in a hermetically sealed system; refrigerating an interior surface of said system; evacuating said system; draining condensate from said refrigerated surface; and passing water vapor from said comestibles in heat transfer relation first with said condensate and then downwardly past said refrigerated surface.

6. A portable vacuum cooling plant comprising in combination: a tractor; a trailer connected to said tractor to be drawn thereby; a hermetic enclosure mounted on said trailer and having a rear access door and conveyor means therein to receive packed produce for treatment in said enclosure; an insulated, hermetically sealable chamber mounted on said tractor having an access door for loading ice into said chamber; a flexible conduit having a quick-disconnect joint therein, said conduit being connected between said chamber and enclosure to intercommunicate the same; an inner compartment in said chamber having an open top to receive said ice and communicate said inner compartment with said chamber, said inner compartment having separate vapor and liquid exit ports adjacent the bottom thereof, and said inner compartment having one vertical wall thereof spaced from a vertical wall of said chamber whereby to form a vertical flue; a vacuum pump mounted on said tractor connected to said vapor exit ports to withdraw air from the enclosed system comprising said inner compartment, chamber, and enclosure; water trap means in said liquid exit ports to prevent counterflow of vapor therethrough; an inclined interior surface in said chamber below said inner compartment to receive condensate and melted ice from said liquid exit ports; and baffle means in said chamber to direct vapor flowing into said chamber from said conduit in heat transfer contact against said inclined surface and thereafter up said flue to enter said inner compartment at said open top thereof.

7. In a vacuum cooling plant of the type having a sealable enclosure to receive material for treatment therein, means to evacuate said enclosure and condense vapor withdrawn therefrom, comprising in combination: an insulated, hermetically sealable chamber having an access door for loading ice into said chamber; a flexible conduit having a quick-disconnect joint therein, said conduit being adapted for connection between said chamber and enclosure to intercommunicate the same; an inner compartment in said chamber having an open top to receive said ice and communicate said inner compartment with said chamber, said inner compartment having separate vapor and liquid exit ports adjacent the bottom thereof, and said inner compartment having one vertical wall thereof spaced from a vertical wall of said chamber whereby to form a vertical flue; a vacuum pump connected to said vapor exit ports to withdraw air from the en-

closed system comprising said inner compartment, chamber, and enclosure; water trap means in said liquid exit ports to prevent counterflow of vapor therethrough; an inclined interior surface in said chamber below said inner compartment to receive condensate and melted ice from said liquid exit ports; and baffle means in said chamber to direct vapor flowing into said chamber from said conduit in heat transfer contact against said inclined surface and thereafter up said flue to enter said inner compartment at said open top thereof.

8. In a vacuum cooling plant of the type having a sealable enclosure to receive material for treatment therein, means to evacuate said enclosure and condense vapor withdrawn therefrom, comprising in combination: an insulated, hermetically sealed chamber; a flexible conduit having a quick-disconnect joint therein, said conduit being adapted for connection between said chamber and enclosure to intercommunicate the same; an inner compartment in said chamber having an open top to communicate said inner compartment with said chamber, said inner compartment having separate vapor and liquid exit ports adjacent the bottom thereof, and said inner compartment having one vertical wall thereof spaced from a vertical wall of said chamber whereby to form a vertical flue; a vacuum pump connected to said vapor exit ports to withdraw air from the enclosed system comprising said inner compartment, chamber, and enclosure; water trap means in said liquid exit ports to prevent counterflow of vapor therethrough; an inclined interior surface in said chamber below said inner compartment to receive condensate from said liquid exit ports; and baffle means in said chamber to direct vapor flowing into said chamber from said conduit in heat transfer contact against said inclined surface and thereafter up said flue to enter said inner compartment at said open top thereof.

9. A portable vacuum cooling plant comprising in combination: a hermetic enclosure having an access door and support means therein to receive packed produce for treatment in said enclosure; a hermetically sealable chamber structurally separate from said enclosure and having refrigerating means to cool an interior surface thereof; a conduit interconnected between said enclosure and chamber, said conduit having a quick-disconnect joint therein to permit physical removal of said chamber from said enclosure; and a vacuum pump connected to said chamber to withdraw air therefrom whereby to cause air and vapor to discharge from said enclosure through said conduit into said

chamber for condensation of said vapor on said refrigerated surface.

10. The construction of claim 9 further characterized in that said refrigerating means includes a body of ice in said chamber.

11. The construction of claim 9 further characterized in that said refrigerating means includes a set of refrigerant circulating coils in said chamber.

10 12. The construction of claim 9 further characterized in that said refrigerating means includes a heat transmitting portion in the wall of said chamber and exterior bunker means to support ice against the exterior surface of said wall portion.

15 13. The construction of claim 9 further characterized by having a sump substantially out of heat transfer relation with said chamber and means interconnecting said sump and chamber to drain condensate from said chamber into said sump.

20 14. The construction of claim 9 further characterized in that said plant includes a tractor-trailer combination with said chamber mounted on said tractor, and said enclosure mounted on said trailer.

25 15. In a portable vacuum cooling system of the class described: a hermetic enclosure having a sealable access door to receive material for treatment in said enclosure; evacuation and condensation means including a chamber having a cold surface therein, a vacuum pump connected to said chamber to evacuate the same, and conduit means connected to said enclosure to inter-

30 communicate said chamber and enclosure, said conduit means including a quick-disconnect joint to permit physical separation of said enclosure and chamber; and means to direct liquid condensate forming on said cold surface to a point

35 40 in said chamber adjacent the influx of vapor and air from said conduit means whereby the air-vapor mixture drawn from said enclosure through said chamber first passes in heat transfer relation past said condensate and then in contact with said cold surface.

MELVILLE W. BEARDSLEY.
